United States Patent Office.

SAMUEL P. CRINS, OF PROVIDENCE, RHODE ISLAND.

Design No. 3,654, dated September 7, 1869.

DESIGN FOR AN ORNAMENT FOR "WILCOX & GIBBS SEWING-MACHINE."

The Schedule referred to in these Letters Patent and making part of the same.

To all whom it may concern:

Be it known that I, SAMUEL P. CRINS, of the city and county of Providence, State of Rhode Island, have originated and designed a new Design for Ornament of Wilcox & Gibbs Sewing-Machines, of which the following is a full, clear, and exact description, reference being had to the accompanying drawings, making part of this specification—

Figure 1 representing the front side view of said design on said sewing-machines.

Figure 2, the back side view.

Figure 3, the front side of lever.

Figure 4, one side, or half of the base of the machine.

A represents a curved line, running upon different parts of the machines, of varying length, according to the size of the part to which it is applied.

B is a serpentine line, intercepting the curved line A, and running the same length, having its beginning and termination at the same point of curved line A.

C represents a leaf, and

D, a half leaf, through both of which the curved line A and the serpentine line B run.

E represents a series of disks, representing grapes, connected by stem F.

G represents a stalk, and

H, runners from the leaf C and half leaf D, in fig. 4.

In fig. 1, the curved line A and serpentine line B are separated from the lower part by the leaf C, grapes E, stem F, and stalk G forming a cluster, so that instead of forming one continuous line, as in fig. 2, it is broken.

In fig. 2, the curved line A and serpentine line B are unbroken.

The design aforesaid is to be applied in gilt or colors.

All the figures represent and unite to form one design for one Wilcox & Gibbs sewing-machine, and are distinguished and different from each other, because the mechanical construction of the sewing-machines forbids the application of every part of the design to every part of the machine. The combination forms one design for application to one of Wilcox & Gibbs sewing-machines, and the respective parts of the design are to be applied to the respective parts of the said sewing-machine.

What I claim as my invention, and desire to secure by Letters Patent, is—

The design for ornament of Wilcox & Gibbs sewing-machines, herein set forth.
